UNITED STATES PATENT OFFICE.

RAYMOND ARCHER, OF REDMOND, OREGON.

GASOLINE ENGINE.

Application filed November 8, 1923. Serial No. 673,464.

To all whom it may concern:

Be it known that I, RAYMOND ARCHER, a citizen of the United States, residing at Redmond, in the county of Deschutes and 5 State of Oregon, have invented certain new and useful Improvements in Gasoline Engines, of which the following is a specification.

This invention is in the way of a gasoline 10 engine, and the object is to provide a light, durable engine of very simple construction. Another object is to eliminate the water cooling system, thus having a positive and more efficient engine in all weather conditions. 15 A further object is to provide an engine with swinging or pivoted cylinders and with connecting rods rigidly joined to the piston heads, thereby keeping the piston in direct line with the crank shaft at all 20 times and thus eliminating friction and developing more power.

In the drawing

Figure 1 is a longitudinal vertical section;

Figure 2 is a front elevation;

25 Figure 3 is a transverse vertical section through a cylinder, A showing the piston on the up stroke;

Figure 4 is a side elevation;

30 Figure 5 is a detail of the timing cylinder;

Figure 6 is a detail of the timing cylinder drive;

Figure 7 is a detail of the cylinder and pivot strap.

35 In carrying out this invention, I provide a stationary cylindrical case 1, the inner periphery thereof tapering to the rear as shown at 2. Bolt holes 3 are provided at the forward end, and an insulated brass 40 ring 4 sets in a groove 5 at the rear end, and a slot 80 is cut in the said case, for a purpose to be later explained. Cylinders 6 are releasably and pivotally strapped to the case 1, the said cylinders having curved 45 arms 7, their ends terminating in the lugs 8. Bolt holes 9 are cored in the lugs 8, said bolt holes 9 registering with bolt holes 10 in the ears 11 of the straps 12, thus forming means for releasably strapping the cylinders 6 to the case 1 through bolts inserted 50 through said holes. Oil grooves 13 are formed in the arms 7. Oil discharge ports 14 connect with the grooves 13 to permit oil to run over the sides of the cylinders 6. 55 Ports 16 which serve the secondary feed pipes 29, the spark plugs 30 and the exhaust

60 pipes 31, are provided in the head of the cylinders 6, said ports 15 registering with elliptic ports 16 of the case 1. Pistons 17 carrying rings 18, slidingly engage the inner peripheries of the cylinders 6. Arms 19 are cast in the pistons 17. The upper ends of connecting rods 20 are rigidly joined to the arms 19 of the pistons 17, while the lower ends terminate in the bearings 21, and 65 the said bearings 21 engage a crank shaft 22. A revolving timing cylinder or rotary valve 23 is provided, its periphery tapering to correspond with the inner periphery of the case 1, and is slidingly mounted in the 70 said case 1. Upon the periphery of the timing cylinder 23, and to the rear of the same gear teeth 24 are cut diagonally, for a purpose to be later explained. Within the forward end of the case 1, a ball bearing 75 race 25 is slidingly mounted; and the ball bearings of the said race engage the forward end of the timing cylinder 23. A bolt 26 is passed through the holes 3 of the case 80 1. The bolt 26 engages a sleeve 27, carrying a spring 28, which bears upon the ball bearing race 25, thus tending to keep the timing cylinder 23 frictionally engaged with the inner periphery of the case 1, yet permitting the said timing cylinder 23 to slip 85 forward upon expansion. Within the timing cylinder 23 are mounted, relatively to the position of the cylinders 6, the secondary feed pipes 29, the spark plugs 30, and the exhaust pipes 31. The ends 32 of the several branches of the main feed pipe 33 pass 90 through the upper section 43 of the supports 40, 41 and 42, and are secured in the upper portion of the wall of the casing 1, and so spaced as to communicate with the secondary feed pipes 29 at the proper times. The ends 34 of the branches of the main 95 exhaust pipe 35 pass through the upper section 43 of the supports 40, 41 and 42, and are secured in the upper portion of the wall of the casing 1, and so spaced as to communicate with the exhaust pipes 31 which 100 communicate with the cylinders 6 upon the up strokes of the pistons 17 after the explosions. The spark plugs 30 follow in rotation one on every quarter section around the inner periphery of the timing cylinder 23, but not longitudinally as shown in Figure 1. The wires 36 of the said spark plugs 30 are run to the rear of the timing cylinder 105 23, and are held securely thereto by means of insulated clamps 37. The end 38 of the

said wires are turned outwardly so as to frictionally engage the brass ring 4 in the case 1. The said brass ring 4 has an insulated connection 78 with the battery wire 39, thus keeping the spark plugs 30 constantly charged with electricity and causing them to function at the proper times. The front and rear ends of the timing cylinder 23 and the case 1 are open, to give passage 10 to a constant flow of air, thus keeping the timing cylinder 23 always cool. The engine supports 40, 41 and 42 are divided into sections. The upper section 43 of the supports 40, 41 and 42 is cast in one piece, and serves 15 as part of the engine housing 44, and also as a bearing shell for the case 1. The said section 43 has grooves 45 to accommodate the straps 12 and keep them in line with the piston bearings 21. Lugs 46, corresponding 20 to lugs 49 of the section 47, are cast on the upper portion of the section 43 to provide means for securing it to the section 47 of the supports 40, 41 and 42. The middle sections 25 47 of the supports 40, 41 and 42 carry in their upper portions bearing recesses for the case 1, while the lower portion carries the upper half of the crank shaft bearings 48. Bearings 49 are cast on the section 47 of the support 42 to provide means for journaling 30 the vertical idler shaft 67 of the timing cylinder drive 50. Bearing recesses 51 and openings 52 are provided in the said section 47 of the support 42, for the shafts and gears of the timing cylinder drive 50. Lugs 35 53 corresponding to lugs 54 of the section 55 are cast on the lower portion of the section 47 to provide means for securing it to the section 55 of the supports 40, 41 and 42. Braced lugs 56 are cast on the sides of the 40 sections 47 of the supports 40, 41 and 42, to provide means for securing the said supports to the frame of a machine. The sections 55 of the supports 40, 41 and 42 carry in their upper portions the lower half of 45 the crank shaft bearings 48. A semi-circular hole 57 is cored in the section 55 of the support 41 to permit oil to run from one compartment to the other. The section 55 of the support 42 houses an oil pump 58 and is cast in two sections. Lugs 59 are 50 cast along the split surface of the section 55 of the support 42 to provide for means for bolting same together. An oil inlet 60 is provided at the side of the pump 58, while 55 an outlet 61 is provided at the bottom of the said pump. The outlet 61 of the pump 58 communicates with the bottom of the radiator by means of a pipe. Pipes 62 having a series of nozzles 63 are connected to 60 the upper portion of the radiator. The nozzles 63 pass through the sides of the housing 44 and are in line with the oil grooves 13 of the cylinders 6. The sheet metal housing 44 is made in sections; the lower sections 65 being provided with petcocks 76 for drain-

ing purposes. A spur gear 64 is mounted on the crank shaft 22 at the rear end. The spur gear 64 meshes with an idler 65. The said idler has a bevel gear 66 formed on its side, which drives a vertical idler shaft 67 70 by means of a bevel gear 68 which passes through the opening 52 of the section 47 of the support 42, and meshes with the bevel gear 66. The upper end of the shaft 67 carries a bevel gear 69 which passes through 75 an opening 52 of the section 47 of the support 42 and meshes with a bevel gear 70 formed on the side of the gear 75. The gear 75 passes through the slot 80 and has diagonally cut teeth which mesh with the 80 teeth 24 of the timing cylinder 23. The spur gear 65 is mounted upon a shaft 71, the one end of which is journaled in one of the bearing recesses 51, and the other end is journaled in the gear housing 73. The 85 gear 70 is mounted upon a shaft 72, the one end of which is journaled in one of the bearing recesses 51, while the other end is journaled in the gear housing 74. A gear 77 mounted at the side of the pump 58 and connected therewith meshes with the gear 64 mounted on the crank shaft 22. A fly wheel 79 is mounted on the crank shaft 22 at the rear end.

In operation, the cylinder being positioned as shown in Figure 1, cylinder A will exhaust upon the up stroke. Cylinder D will be charged with gas on the down stroke. Cylinder B is firing, causing it to make the down stroke. Cylinder C will compress the gas on the up stroke. Cylinder C follows cylinder B in firing, after which cylinder D fires, being followed by cylinder A. An electric current passing through the battery wire 39 keeps the ring 4 charged with electricity. The ends 38 of the spark plug wires 36 frictionally engage the ring 4, thus keeping the spark plugs 30 charged with electricity. The gear ratio of the timing cylinder drive 50 is two to one, the crank shaft 22 making two complete revolutions to the timing cylinder's one revolution. The diagonally cut teeth 24 on the timing cylinder 23 and on the gear 75 have a tendency to work the said timing cylinder forward, thus permitting it to work with the greatest efficiency, whether the timing cylinder is cold and contracted, or warm and expanded. The spring 28, bearing upon the ball bearing race 25, keeps the periphery 110 of the timing cylinder 23 frictionally engaged with the inner periphery of the case 1, allowing the timing cylinder 23 to slip forward just enough to take care of the expansion of the said timing cylinder. A constant flow of air passing through the inside of the timing cylinder 23 keeps it cooled. The cylinders 6 are cooled by oil pumped out of the housing 44 by the oil pump 58, and forced through a radiator into 115 120 125 130

the pipes 62 and through the nozzles 63, which terminate at the side of the case 1, permitting the oil to flow into the grooves 13 and over the sides of the case 1. While 5 I have herein described a certain specific manner and method of constructing and assembling the elements of my invention, it is understood that I may vary from the same in minor details, not departing from the 10 spirit of my invention, so as best to construct a practical device for the purpose intended, as defined in the appended claims.

I claim:

1. In a device of the kind described, the 15 combination of which comprises supports, having a case open at both ends and provided with common intake and exhaust ports in its lower side, and having its inner periphery tapered, mounted therein; a tapered 20 timing cylinder open at both ends, rotatively mounted in the case; independent secondary feed and exhaust pipes mounted substantially diametrically thru the case communicating with the common intake and exhaust 25 ports of the case; independent primary feed and exhaust pipes secured on a common center in the case, communicating with the secondary feed and exhaust pipes; cylinders pivotally strapped to the case; a crank shaft 30 journaled in the supports below the cylinders; pistons reciprocatingly mounted in the cylinders, journaled to the crank shaft by means of rigid connecting rods; a housing secured to the supports; and means for firing the explosive mixtures.

2. In a gasoline engine embodying a housing; a crank shaft mounted within the said housing; a cylindrical case open at both ends mounted in the housing, its inner periphery 40 tapering from the front end to the rear; a timing cylinder open at both ends rotatively mounted within the said case, its periphery tapering from the front end to the rear, corresponding to the inner periphery of the said cylindrical case; cylinders pivotally strapped to the cylindrical case; pistons reciprocatingly mounted in the said cylinders and connected with the crank shaft.

3. In a gasoline engine of the kind described, embodying a housing; a crank shaft mounted within the said housing; a cylindrical case open at both ends mounted in the housing, its inner periphery tapering from 50 the front end to the rear; a timing cylinder open at both ends rotatively mounted with-

in the case, its periphery tapering from the front end to the rear, corresponding to the inner periphery of the said cylindrical case; means for keeping the timing cylinder snugly engaged with the said case; cylinders pivotally strapped to the cylindrical case; and pistons reciprocatingly mounted in the said cylinders and connected with the crank shaft.

4. In a gasoline engine of the kind described, embodying a housing; a crank shaft mounted within the said housing; a cylindrical case open at both ends mounted in the housing, its inner periphery tapering from the front end to the rear; a timing cylinder open at both ends rotatively mounted within the said case, its periphery tapering from the front end to the rear, corresponding to the inner periphery of the said cylindrical case; a ball bearing race engaging the one end of the timing cylinder; a flat spring anchored in the case, engaging the ball bearing race for keeping the timing cylinder snugly engaged with the said case; cylinders pivotally strapped to the cylindrical case; pistons reciprocatingly mounted in the said cylinders; and connecting rods rigidly secured to the pistons and engaging the crank shaft.

5. In a gasoline engine embodying a housing; a cylindrical case open at both ends, mounted in the housing, its inner periphery tapering from the front end to the rear; feed and exhaust pipes secured in the case; a tapered timing cylinder rotatively mounted in the cylindrical case; secondary feed and exhaust pipes mounted in the timing cylinder; an insulated brass ring having a terminal secured thereto mounted in the cylindrical case; clamps rigidly secured in the timing cylinder on a common center line on every 90 degrees of the inner periphery of the timing cylinder; spark plugs mounted in the timing cylinder on a common center with the cylinders and in a longitudinal zig-zag formation at every 90 degrees of the inner periphery; feed wires engaging the insulated brass ring, secured in the clamps and to the spark plugs; cylinders pivotally strapped to the cylindrical case; pistons reciprocatingly mounted in the cylinders; and connecting rods rigidly secured to the pistons engaging the crank shaft.

In testimony whereof I affix my signature.
RAYMOND ARCHER.
